UNITED STATES PATENT OFFICE.

CHARLES D. ORCUTT, OF DAYTON, OHIO.

DESIGN FOR A STOOL.

SPECIFICATION forming part of Design No. 36,265, dated March 31, 1903.

Application filed March 2, 1903. Serial No. 145,844. Term of patent 7 years.

To all whom it may concern:

Be it known that I, CHARLES D. ORCUTT, a citizen of the United States, residing at Dayton, in the county of Montgomery and State of Ohio, have invented a certain new, original, and ornamental Design for a Stool; and I do declare the following to be a full, clear, and exact description of the invention, such as will enable others skilled in the art to which it appertains to make and use the same, reference being had to the accompanying drawing, and to the letters of reference marked thereon, which forms a part of this specification.

The drawing is an elevation of a stool made in accordance with my new and ornamental design.

The leading or distinguishing characteristics of the design consist in a leg A, which terminates at its upper end B in a representation of an animal's face with mouth open, disclosing teeth. The leg as it approaches the

lower end partakes of the decided curvature inwardly; and the lower extreme end thereof projects outwardly and terminates in a caster C. The leg on each side of the animal's face 25 has a series of wave-like ornamentations D in representation of hair. Between each two of said legs there is skirting E in representation of drapery looped in the middle and having ends terminating adjacent to the said legs. 30 The stool consists of an upholstered body F.

Having described my invention, what I claim as new, and desire to secure by Letters Patent, is—

The ornamental design for a stool as here- 35 in shown and described.

In testimony whereof I affix my signature in presence of two witnesses.

CHARLES D. ORCUTT.
